UNITED STATES PATENT OFFICE.

HENRY E. WINANS, OF ALTON, ILLINOIS, ASSIGNOR TO WESTERN CARTRIDGE COMPANY, OF EAST ALTON, ILLINOIS, A CORPORATION OF DELAWARE.

TARGET TRAP.

Application filed December 1, 1924. Serial No. 753,212.

This invention relates to target traps, such as are used for throwing one or more targets into the air to imitate the flights of birds for the practice of marksmanship.

One of the objects of this invention is to provide a novel method of throwing targets from a trap.

Another object is to provide a target trap of novel construction adapted to simplify the handling of the targets thereon.

Another object is to provide such a trap with simplified arrangements for determining the direction of flight of the targets.

Another object is to provide an improved construction of material substantially proof against deterioration.

Further objects will appear from the detail description taken in connection with the accompanying drawings, in which—

Figure 1 is a side view showing a target trap embodying this invention;

Figure 2 is a plan view of the same;

Figure 3 is an enlarged detail sectional view showing the construction of the guide for the throw arm; and

Figure 4 is an enlarged section on line 4—4, Figure 2.

Referring to the accompanying drawing, 1 designates a frame having at its rearward end a standard 2 and at its forward end a standard 3. The frame 1 is pivoted at 4 to a support 5 upon which it is adjustably mounted so that it may be tilted at different angles, the same being fixed by a clamping bolt 6. The support 3 is provided at its upper end with a short shank 7 upon which is fixed the hub 8 of a spider having arms 9 and a circumferential rim 10. The rim 10 is provided with a circumferential groove 35 adapted to receive the edge of a flat glass plate 11. The plate 11 is preferably of plate glass so as to have a smooth top surface which will not be corroded or otherwise affected by the weather.

The standard 3 supports an up-right shaft 12 which carries at its upper end a throw-arm 13. The arm 13 is adapted to swing on the shaft 12 as a pivot so as to move over the surface of the plate 11 at a slight distance thereabove. The arm 13 may be provided with an edge or facing 14 of rubber or other suitable material adapted to engage a target lying on the plate 11. The outer end of the arm 13 has a bent-over end 55 provided with a notch 16 adapted to en-

gage a sear 17 slidably mounted on the standard 2 for movement to the right and left, Figures 1 and 2, and guided by a pin 18 working in a slot 19 in the sear. The sear is held in retracted position by a spring 20 as seen in Figure 1. When the sear 17 is engaged in the notch 16, the throw-arm 13 is retained in the position of Figure 2.

The shaft 12 has fixed thereto an arm 21 provided with a pin 22 to which is fixed one end of the throw-arm spring 23, the other end of which is anchored to an adjusting bolt 24 on the standard 2. The bolt 24 is provided with a wing-nut 25 by means of which the tension of the spring 23 may be adjusted. It will be clear that when the spring 23 is tensioned while the arm 13 is in the position of Figure 2, releasing the arm by moving the sear 17 to the right, Figure 2, out of the notch 16 will cause the arm 13 to swing on its pivot 12 over the plate 11. The end of the arm 13 is provided with a downward extension 26 which carries a roller 27 adapted to engage a circumferential slot 28 in the rim 10. This roller and slot 28 provide means for guiding the arm 13 in its movement over the plate 11 so as to keep it at a uniform distance from the plate.

The shaft 12 carries a sprocket 29 which is engaged by a chain 30 connected to an actuator 31 pivoted at 32 on the standard 2. The actuator 31 is connected by means of an operating rod or tube 33 with the operator's stand at the firing point so that it may be operated from that point. The element 33 is preferably a stiff rod or tube capable of transmitting a thrust as well as a pull. Tension on the rod 33 operates to move the actuator 31 to the left, Figure 1, thereby, through the agency of the chain 30, rotating the sprocket 29 and the shaft 12 against the tension of the spring 23 so as to swing the arm 13 rearwardly until the sear 17 engages in the notch 16 to set the trap. Pivoted at 34 on the actuator 31 is a trigger 35 provided at one end with an abutment 36 adapted to engage the rear end of the sear 17. The trigger 35 is provided at its other end with an abutment 37 adapted to engage a stationary abutment 38 on the standard 2 when the actuator is moved to the right, Figure 1. It will be seen that by this construction the trap may be set by a pull to the left, Figure 1, on the rod 33 and released by a thrust to the right. The thrust to the right

will swing the actuator 31 to the right about its pivot 32 until the abutment 37 comes into engagement with the abutment 38, whereupon further movement of the actuator will cause the trigger 35 to swing about its pivot 34 until the abutment 36 comes into contact with the end of the sear 17. On account of the rapid movement of the actuator, this contact takes place by a sharp impact of the abutment 36 on the sear so as to force the sear to the right to release the throw arm 13. One of the arms 9 is provided with a boss 39 having a plane face 40 against which the head 41 of a T-shaped guide or stop 42 may bear. The head 41 is provided with an elongated slot 43 extending along the head and adapted to slide on a screw 44 threaded into the boss 39. The screw 44 is adapted to fix the guide 42 in adjusted position along the arm 9. The construction is such that when the head 41 is clamped against the face 40 of the lug, the blade or shank of the stop 42 will lie upon the plate 11 and extend in a direction substantially at right angles to that of the arm 13 in the position of Figure 2.

In the use of this device the trap having been set, one or more targets may be laid upon the plate 11 as illustrated in Figure 2. These targets are ordinarily constructed of light pottery and have a circular outline with a dished body. These targets are ordinarily provided with a relatively thin outer rim or flange 45 adjoining the body portion 46. The arm 13 is spaced from the plate 11 so that it will just pass over the flange 45 of a target resting on the plate and engage the body portion 46. One or more targets may be launched from the trap at the same time. When two targets are launched together, they are placed as illustrated in Figure 2, the target A being placed so as to rest against the face 14 of the throw arm and with its rim 45 against the edge of the stop 42 which has been adjusted previously so as to position this target as shown. The second target B is placed so as to rest against the face 14 similarly to the first target and to abut the first target at its rim as shown in Figure 2. When only one target is thrown, it is placed in the position of the target B, the stop 42 being readjusted to the position shown in dotted lines in Figure 2. With the targets in this position, when the throw-arm is released it will sweep the targets across the plate 11 with a sliding movement. At the same time the targets will move outwardly, rolling along the arm at the same time that they slide over the plate 11. Thus the targets are launched with a rotary and sliding movement over the plate. The travel of each target across the plate will be approximately as indicated in the dotted lines C and D in Figure 2. Since the movement of the throw-arm is very rapid,

both targets are launched with considerable velocity as they leave the plate and also have imparted to them a rotary or whirling movement which insures a sailing flight as is desirable in this form of marksmanship practice.

The flight of the target may be controlled in elevation by adjusting the angle or tilt of the plate. This is done by adjusting the tilt of the frame 1 on the pivot 4. The flight of the targets laterally or in any direction may be controlled by suitably adjusting the position of the stop 42. This adjustment fixes the initial location of the target on the plate. Varying such location will vary the path of the target over the plate during the throwing movement and will vary the point of departure or the part of the plate at which the target leaves the same.

It will be seen, therefore, that this invention accomplishes its objects. A novel method of throwing targets from a trap is provided in which the targets are swept from a smooth plate with a combined sliding and rotary motion over the plate so as to impart the proper rotation to the target in its flight. The use of a glass plate insures that a permanently smooth top will be provided which will be unaffected by weather conditions or other conditions tending to corrode or otherwise destroy the surface of other materials. The construction is such that the flight of the targets may be controlled both in elevation and direction by the adjustments described. The rapidity of handling such a trap is also increased on account of the fact that there are no sockets or gripping fingers into which the targets must be inserted. The targets are simply laid on the plate and pushed quickly into their proper places.

It is obvious that various changes may be made in details of construction without departing from the spirit of this invention; it is, therefore, to be understood that this invention is not to be limited to the specific details shown and described.

Having thus described the invention, what it claimed is:—

1. A target trap, comprising, a glass plate adapted to receive the target, a throw arm mounted for movement over said plate and adapted to engage the target, and means for moving said arm.

2. A target trap, comprising, a glass plate adapted to receive the target, a throw arm mounted for movement over said plate and adapted to engage the target, means for moving said arm, and means for guiding said arm over said plate.

3. A target trap, comprising, a flat glass plate adapted to receive the target, an arm pivoted adjacent said plate and adapted for swinging movement thereover to launch the target, means for moving said arm, and

means for adjusting said plate to direct the target.

4. A target trap, comprising, a flat glass plate adapted to receive the target, an arm pivoted adjacent said plate and adapted for swinging movement thereover to launch the target, means for moving said arm, and a guide for said arm adjacent said plate.

5. A target trap, comprising, a flat glass plate adapted to receive the target, an arm pivoted adjacent said plate and adapted for swinging movement thereover to launch the target, means for moving said arm, and a rim for said plate adapted to guide said arm in a uniform path relatively to said plate.

6. A target trap, comprising, a flat glass plate adapted to receive the target, an arm pivoted adjacent said plate and adapted for swinging movement thereover to launch the target, means for moving said arm, and a

stop adjustable over said plate to locate the target.

7. A target trap, comprising, a flat glass plate adapted to receive a plurality of targets, a throw arm pivoted for movement over said plate to launch the targets, means for moving said arm, and a stop adjustable over said plate to locate the targets initially on said plate in order to determine the directions of their flights.

8. A target trap, comprising, a flat glass plate adapted to receive a plurality of targets, a throw arm pivoted for movement over said plate to launch the targets, means for moving said arm, and a stop adjustable over said plate to locate the targets initially on said plate so as to launch the targets from different parts of said plate.

In testimony whereof I affix my signature this 17th day of November, 1924.

HENRY E. WINANS.
